UNITED STATES PATENT OFFICE.

PERRY W. TURNER, OF ADA, OHIO.

METAL ROOFING.

No. 836,157.

Specification of Letters Patent.

Patented Nov. 20, 1906.

Application filed May 16, 1906. Serial No. 317,189.

To all whom it may concern:

Be it known that I, PERRY W. TURNER, a citizen of the United States, residing at Ada, in the county of Hardin and State of Ohio, have invented certain new and useful Improvements in Metal Roofings; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to improvements in metal roofing, and relates more especially to roofing with which muslin, canvas, or other fibrous material is employed, the same being connected with the metal sheets by the use of adhesive and preservative substance having the nature of paint.

In my improved roofing I employ either corrugated, beaded, or flat sheets of material, as may be desired. In manufacturing this roofing I apply the adhesive paint substance to the surface of the metal, which is to be underneath when in use. I then apply the fibrous material to this painted surface, the paint causing the fibrous material to adhere. I also allow the fibrous material to project beyond the metal sheet on one side and one end, so that when these sheets are applied to a roof the marginal portions shall overlap the adjacent metal sections and lie on top of the same. In the use of these prepared metal sheets their metal portions are also made to overlap, preferably in such a manner that the fibrous material marginal portions are on the outside. In this way perfectly tight joints are formed. When the prepared sheets are placed upon the roof, the marginal canvas portions, or those projecting beyond the metal, should be saturated with paint by applying it to one or both sides, as may be necessary or desirable.

The invention will possibly be better understood by reference to the accompanying drawings, in which—

Figure 1 shows a sheet of metal constructed in accordance with my invention, the metal portion being corrugated. Fig. 2 is a section taken through the same on the line 2-2, Fig. 1. Fig. 3 is a section taken through two of the prepared sheets applied to the roof, one of the sheets, however, being shown without the fibrous margin, because it is the initial section. Fig. 4 shows a number of

sheets, on a smaller scale, as they would appear when in use. In this case the parts shaded with the intersecting diagonal lines indicate the marginal canvas portions. Fig. 5 is a cross-section taken on the line 5-5, Fig. 4. Fig. 6 is a perspective view of a piece of prepared material in which the metal part is beaded or composed of a different pattern of corrugation than in Figs. 1 and 3.

The same reference characters indicate the same parts in all the views.

Let the numeral 5 designate the corrugated metal sheet to whose under surface is applied muslin or other fibrous material 6, which protrudes at one side, as shown at 6^a, and at one end, as shown at 6^b. In Fig. 4 the metal parts of the sections or sheets are flat and are designated 5^a, while the marginal canvas or muslin portions are designated 6^a and 6^b, the same as in Figs. 1 and 3. Referring to Fig. 6, the metal part of the section or sheet is designated 5^b and the canvas or muslin portion 5^c. In this case the fibrous material is doubled, as shown at 5^c and forced into the ribs 8^c 5^d of the metal portion on the under side, as shown in Fig. 6.

There are many different patterns of the metal sheet that may be employed. The main feature of the invention, however, does not relate to the special pattern, but consists in the fact that the muslin is applied to the under side of the metal sheet and allowed to protrude or project therefrom in order to overlap the metal and form an exceedingly tight joint. Moreover, by placing the fibrous material on the under side, the roof is protected from the gases which may arise from the inside of the building, as is often the case during the carrying out of the processes for the treating of ores. Some of these gases are very injurious to roofs composed of ordinary material. Hence it is usually more desirable on buildings where metal roofs are employed to have the inside of the metal sheet protected rather than the outside, since the influences from within are more destructive than those from without.

Having thus described my invention, what I claim is—

1. As an improved article of manufacture, roofing material consisting of sheet metal and fibrous material applied to the metal by the use of an adhesive preservative substance, the fibrous material being allowed to project beyond the edges of the metal.

2. As an improved article of manufacture,

a roofing-plate composed of sheet metal and fibrous material applied to the under side thereof and allowed to project from one side and one end.

5. 3. A roof composed of sheets of material made up of a body portion of sheet metal and a lining of fibrous material which protrudes from two edges, the said sheets being applied to the roof in such a manner that the protruding fibrous or marginal portions of the sheets are located on the outside.

4. A roofing-plate composed of sheet metal and fibrous material applied to the inner surface thereof by the use of a suitable adhesive preservative substance, the fibrous material

protruding from the sheet-metal portion, substantially as described.

5. A roofing-plate composed of corrugated sheet metal, and fibrous material applied to the inner surface thereof and projecting into 20 the corrugations thereof, the fibrous material protruding from the sheet-metal portion, substantially as described.

In testimony whereof I affix my signature in presence of two witnesses.

PERRY W. TURNER.
